US00D612227S

(12) **United States Design Patent**
Banasik et al.

(10) **Patent No.:** **US D612,227 S**
(45) **Date of Patent:** **** Mar. 23, 2010**

(54) **WORKPIECE FINISHING SUPPORT**

(75) Inventors: **Daniel Banasik**, Eagan, MN (US);
Steven Krohmer, Coon Rapids, MN (US)

(73) Assignee: **Rockler Companies, Inc.**, Medina, MN (US)

(**) Term: **14 Years**

(21) Appl. No.: **29/332,004**

(22) Filed: **Feb. 6, 2009**

(51) **LOC (9) Cl.** **08-05**

(52) **U.S. Cl.** **D8/367**

(58) **Field of Classification Search** **D8/301, D8/302, 367, 371, 372, 373, 382, 395; D10/83, D10/99; 248/74.2, 100, 201, 214, 215, 216.1, 248/218.1, 231, 231.91, 243, 301, 302, 303, 248/304, 309.1, 322, 339, 340, 467, 493, 248/496, 497, 498, 547; 16/413; 24/265 H, 24/563, 907; 211/13.1, 60.1, 65, 66, 87.01; 404/134; D19/34.1, 91; D6/323, 553; D26/37; D22/149**
